US00D626054S

(12) **United States Design Patent**
Walthert

(10) **Patent No.:** **US D626,054 S**
(45) **Date of Patent:** **** Oct. 26, 2010**

(54) **SPOKE**

(75) Inventor: **Martin Walthert**, Bern (CH)

(73) Assignee: **DT Swiss Inc.**, Grand Junction, CO (US)

(**) Term: **14 Years**

(21) Appl. No.: **29/299,701**

(22) Filed: **Jan. 2, 2008**

(30) **Foreign Application Priority Data**

Jul. 2, 2007 (DE) 4 07 03 313

(51) **LOC (9) Cl.** **12-15**

(52) **U.S. Cl.** **D12/213**

(58) **Field of Classification Search** D12/213;
301/37.101, 64.101, 65, 55, 111.01, 104

See application file for complete search history.

(57) **CLAIM**

The ornamental design for a spoke, as shown and described.

DESCRIPTION

FIG. 1 is a side view of the present spoke, both sides being identical;

FIG. 2 is a front view of the spoke of FIG. 1, the rear being identical;

FIG. 3 is a bottom view of the spoke of FIG. 1;

FIG. 4 is a bottom view of the spoke as shown in FIG. 2;

FIG. 5 is an enlargement of the spoke as shown in FIG. 3;

FIG. 6 is a top view of the spoke of FIG. 1;

FIG. 7 is side view of an alternate embodiment of the spoke of FIG. 1, both sides being identical;

FIG. 8 is a front view of the spoke of FIG. 7, the rear view being identical; The top and bottom views of the spoke of FIG. 7 being identical to that of FIG. 1;

FIG. 9 is a side view of another alternate embodiment of the present spoke, both sides being identical;

FIG. 10 is a front view of the spoke of FIG. 9, the rear view being identical;

FIG. 11 is a bottom view of the spoke of FIG. 9, the top view being identical;

FIG. 12 is an enlargement of the spoke as shown in FIG. 11;

FIG. 13 is a front view of another embodiment of the present spoke, the rear being identical;

FIG. 14 is a side view of the spoke of FIG. 13, both sides being identical;

FIG. 15 is a bottom view of the spoke of FIG. 14, the top view being identical; and,

FIG. 16 is a bottom view of the spoke of FIG. 13, the top view being identical.

The structures shown in broken lines are submitted for environment purposes only and do not form part of the claimed invention.
